CLAMPING DEVICE FOR TOOL STANDARDS

Alvah E. Rutter, Rockford, Ill., assignor to J. I. Case Company, Racine, Wis., a corporation

Original application October 16, 1941, Serial No. 415,153. Divided and this application November 12, 1943, Serial No. 510,049

9 Claims. (Cl. 97—198.1)

1

The present invention relates to plows and more particularly to disk plows, and an object of the invention is to generally improve the construction and operation of implements of this class. Another object is to improve such a plow in respect to the adjustments thereof.

A further object is to provide improved adjustments of the disks of such a plow to provide for different conditions of operation.

Further objects are to provide improved expedients for the realization of the above objects.

Further objects and advantages will become apparent from the following specification and annexed drawings in which

Figure 1 is a right side elevation looking diagonally forward of so much of a disk plow as necessary to illustrate the invention.

Fig. 2 is a similar view with parts removed.

Fig. 3 is a similar view with parts broken away but not otherwise in section.

Fig. 4 is a view similar to Fig. 1 but with the parts in a substantially different arrangement.

The parts illustrated are used in and constitute parts of a disk plow of the type shown and described in the co-pending application of Alvah E. Rutter, Serial 415,153, filed October 16, 1941, now Patent Number 2,351,369, patented June 13, 1944, of which this application is a division. Such a plow includes a beam 10 suitably supported at the front and rear and constituting in effect a main frame element for the plow. Beam 10 carries a series of rotatable cutting blades or disks 11, only one of which is necessary to be described in the present application, united with beam 10 by standards 12, the whole being drawn by a tractor or the like not shown, in a manner generally well known and fully disclosed in the above identified co-pending application.

Standards 12 are arranged to be clamped on beam 10 in various positions as required by plowing conditions, as is well known. Since the standards are preferably all alike, it will be necessary to describe only one, as in the case of disks 11. Standard 12 is clamped against a plate generally designated as 13 which is clamped against beam 10 as will appear. In the present instance, U-bolts generally designated as 14 and 15 embrace the back side of beam 10 as seen in Fig. 1, U bolt 14 having a portion 16 extending forwardly through plate 13 above beam 10 and at the rear of standard 12. Bolt 14 also has a portion 17 extending forwardly through plate 13 below beam 10 and also at the rear of standard 12. In similar manner bolt 15 has a portion 18 extending forwardly above beam 10 and forwardly of standard 12, and a portion 19 extending through plate 13 below beam 10 and forwardly of standard 12. Portions 17 and 19 are spaced by plate 13 so as to admit standard 12 between them but without more than necessary clearance, while portions 16 and

2

18 are spaced so as to allow very considerable clearance for standard 12. Standard 12 may therefore be said to be in effect pivoted between bolt portions 17 and 19, while portions 16 and 18 act as stop means to limit the pivot movement by checking fore-and-aft movement of the upper portion of standard 12.

Plate 13 as more particularly shown in Fig. 2 has a slot 20 which may conveniently or preferably be arcuate in character and through which extends a pin 21, Fig. 3, engaged in one or another of holes as 22—22 in standard 12 to support the standard against appreciable up-and-down movement. Pin 21 guides standard 12 in arcuate movement about an imaginary center between bolt portions 17 and 19 whereby in effect the pivotal movement is secured without weakening standard 12 by piercing for an actual pivot in the neighborhood of bolt portions 17 and 19. Different sizes of disks such as 11 can be readily accommodated by placing pin 21 in the appropriate one of holes 22.

As seen in Fig. 3, standard 12 is clamped to plate 13 in the present instance by a plate 23 engaged by nuts 24 and 25 on bolt portions 16 and 18, pin 21 preferably passing through plate 13 which has a slot 26 similar to above mentioned slot 20. Pin 21 may be maintained in position by a cotter pin or the like 27, a washer 28 being interposed if desired. Another plate 29 is engaged by nuts 30 and 31 on bolt portions 17 and 19 so as to be clamped against standard 12 and to unite it and plate 13 with beam 10. A structure is thus provided in which standard 12 may be disposed at any desirable angle with beam 10 and in which the whole assembly, or point of attachment of standard 12 may be shifted along beam 10 to any desirable point.

In order not to depend upon the clamping effect of bolts 14 and 15, however, for maintaining the angular adjustment of standard 12, a block generally designated as 32 is provided having an opening for receiving bolt portion 18. Since the reaction of the plowing force is in such a direction as to continuously force the upper end of standard 12 toward the front of the plow, block 32 is in position to receive this forward thrust of standard 12 and positively maintain the standard in adjusted angular position independently of the clamping force of bolts 14 and 15. The block may have any convenient shape within the contemplation of the invention, but in the illustrated embodiment is formed as an irregular polygon, the sides of which are of different lengths and of different spacings from the center of bolt 18. As indicated, the sides may be numbered at 33, 34 and 35, etc., so that it will be convenient to set all the standards in the plow in the same adjustment or to return at a later time to a previous adjustment. As will be apparent, block 32

is maintained between plates 13 and 23 and when the parts are assembled they cannot inadvertently get out of adjustment.

As will be understood, standard 12 carries a support element 36 fixed therewith as by bolts 37-37 and carrying a bearing portion 38 journaled on portion 36 in any suitable or well-known manner not shown, and not comprising any part of the present invention. Portion 38 is united to disk 11 by any suitable means as by bolts 39.

Bolt portions 16 and 18 may be spaced to provide any range of adjustment of standard 12 desired and in the present instance block portion 32 as shown in Fig. 4 may be placed on bolt portion 16 if desired, to hold standard 12 in an extreme forward position, under these conditions standard 12 being preferably, although not necessarily, in contact with bolt portion 18. With such adjustment, disk 11 will be brought substantially into the position of a so-called one-way disk plow, namely on a substantially horizontal axis. This adjustment of the disk is especially desirable for trash covering and insofar as applicant is aware, has never before been possible with a plow of the type disclosed having individual standards. With the parts in the position shown in Fig. 4, plates 23 and 29 and nuts 24, 25, 30 and 31 clamp the parts rigidly together as above described. It will be noted that bolts 14 and 15 are preferably fitted so as to have no substantial vertical clearance about beam 10 so that in normal operation of the apparatus bolt portion 18 bears downwardly on the top of beam 10 while bolt portion 17 bears upwardly against the underside of beam 10. This in connection with above mentioned block 32 provides positive means for resisting the thrust without depending upon the frictional engagement between the beam and the several plates and standard 12. This applies particularly to the angle adjustment. The frictional engagement in the past has ordinarily been ample to prevent bodily displacement of prior clamping means but at times insufficient to maintain angular adjustment.

The operation of the invention is thought to be clear from the above description, it being noted that the standards as 12 may be adjusted angularly relatively to beam 10 and the adjustment positively maintained independently of any clamping effect of bolts 14 and 15, and for trash covering or operating as a one-way disk plow, an entirely different positive adjustment of standard 12 can be obtained by placing block 32 on bolt portion 16.

The above being a complete description of an illustrative embodiment of the invention, what is claimed as new and desired to be secured by Letters Patent of the United States is:

1. In a clamping device for uniting a substantially horizontal beam and an upright standard in a disk plow, the combination of a substantially vertical plate, bolt portions spaced apart and extending transversely through the plate, other bolt portions extending transversely through the plate, spaced apart a greater distance than the above mentioned bolt portions and vertically spaced from said above mentioned bolt portions, a spacer block adjustably carried by one of the last mentioned bolt portions and having a plurality of surfaces spaced at varying distances from said bolt portion, said surfaces being adapted to engage said standard respectively in different positions of said spacer block to positively maintain the adjustment of the standard in various predetermined positions, and clamping mechanism carried by said bolt portions.

2. A clamping and adjusting device for a standard of a disk plow having a beam, said device comprising a clamp engaging the beam and including a U-bolt engaged about the beam and having upper and lower portions passing respectively above and below the beam, a second U-bolt spaced along the beam from the first U-bolt, engaged about the beam and having upper and lower portions passing respectively above and below the beam, a standard adapted to be clamped and disposed between the lower bolt portions and also between the upper bolt portions, the spacing of the lower bolt portions being such as to provide for pivotal adjustment of the standard about a point in the region of the lower bolt portions by sliding between the limits defined by the upper bolt portions, a spacer block disposed on one of the upper bolt portions and having a plurality of surfaces spaced at varying distances from said bolt portion, said surfaces being adapted to engage said standard respectively at different positions of said spacer block to positively maintain the adjustment of the standard, and clamping mechanism on the bolt portions for clamping the beam and standard together.

3. A clamping and adjusting device for a disk plow having a beam, said device comprising a clamp engaging the beam and including a U-bolt engaged about the beam and having upper and lower portions passing respectively above and below the beam, a second U-bolt spaced along the beam from the first U-bolt, engaged about the beam and having upper and lower portions passing respectively above and below the beam, a standard adapted to be clamped and disposed between the lower bolt portions and also between the upper bolt portions, the spacing of certain of said bolt portions being such as to provide for pivotal adjustment of the standard about a point in the region of said bolt portions by sliding between the limits defined by the other bolt portions, a spacer block disposed on one of the upper bolt portions and having a plurality of surfaces spaced at varying distances from said bolt portion, said surfaces being adapted to engage said standard respectively in different positions of said spacer block to positively maintain the adjustment of the standard in various predetermined positions, and clamping mechanism on the bolt portions for clamping the beam and standard together.

4. A clamping and adjusting device for a standard of a disk plow having a beam and front supporting means and rear supporting means for the beam, said device comprising a clamp engaging the beam and including a plate adapted to be clamped against said beam, a standard adapted to be clamped against the plate, means pivotally engaging the standard with the plate for adjustment of the angle of the standard relatively to the beam, spaced abutment means so disposed as to limit the possible pivotal movement of said standard, a spacer member selectively engageable with one or the other of said abutment means and having a plurality of surfaces spaced at varying distances from the abutment means with which it is engaged, said surfaces being adapted to engage said standard respectively at different positions of said spacer member for positively maintaining the adjustment of said standard, and means including said abutment means for clamping said plate, beam and standard together.

5. A clamping and adjusting device for a standard of a disk plow, said plow having a beam

and front supporting means and rear supporting means for the beam, said device comprising a clamp engaging the beam and including a plate adapted to be clamped against said beam, clamping bolt portions extended in spaced relation through the plate below the beam at either side of said standard, other spaced bolt portions traversing the plate above the beam on either side of said standard, the spacing of the latter bolt portions being such as to provide for pivotal adjustment of said standard by sliding between the limits defined by the latter bolt portions, a spacer block pivoted on one of the latter bolt portions and having a plurality of surfaces spaced at varying distances from the pivotal connection, said surfaces being adapted to engage said standard respectively in different positions of said spacer block to positively maintain the adjustment of the standard in various predetermined positions, and means on the bolt portions for clamping the plate, beam and said standard together.

6. A clamping and adjusting device for a standard of a disk plow, said plow having a beam and a front supporting means and rear supporting means for the beam, said device comprising a clamp engaging the beam and including a plate adapted to be clamped against said beam, clamping bolt portions extended in spaced relation through the plate below the beam at either side of said standard, other spaced bolt portions traversing the plate above the beam on either side of said standard, the spacing of the latter bolt portions being such as to provide for pivotal adjustment of said standard about a point in the region of the first mentioned bolt portions by sliding between the limits defined by the latter bolt portions, a spacer block disposed on one of the latter bolt portions to engage said standard and having a plurality of surfaces spaced at varying distances from said bolt portion to positively maintain the adjustment of said standard in various positions, and means on the bolt portions for clamping the plate, beam and standard together.

7. A clamping and adjusting device for a standard of a disk plow, said plow having a beam and a front supporting means and rear supporting means for the beam, said device including a clamp engaging the beam and including a plate adapted to be clamped against said beam, clamping bolt portions extended in spaced relation through the plate below the beam at either side of said standard, other spaced bolt portions traversing the plate above the beam on either side of said standard, the spacing of the latter bolt portions being such as to provide for pivotal adjustment of said standard by sliding between the limits defined by the latter bolt portions, a pin and slot connection between said standard and said plate for substantially preventing endwise movement of said standard without interference with pivotal adjustment thereof, a spacer block disposed on one of said bolt portions and having a plurality of surfaces spaced at varying distances from said bolt portions, said surfaces being adapted to engage said standard respectively in different positions of said spacer block to positively maintain the adjustment of said standard, and means on the bolt portions for clamping the plate, beam and said standard together.

8. A clamping and adjusting device for a standard of a disk plow, said plow having a beam

and a front supporting means and rear supporting means for the beam, said device including a clamp engaging the beam and including a plate adapted to be clamped against said beam, clamping bolt portions extended in spaced relation through the plate below the beam at either side of said standard, other spaced bolt portions traversing the plate above the beam on either side of said standard, the spacing of the latter bolt portions being such as to provide for pivotal adjustment of said standard by sliding between the limits defined by the latter bolt portions, said standard providing a plurality of vertically disposed holes and said plate providing a substantially horizontally disposed slot, a pin traversing one of said holes and said slot for substantially preventing endwise movement of said standard while providing for pivotal adjustment thereof, said pin being engageable with others of said holes

10 for predetermining the length of said standard below said beam, a spacer block disposed on one of the latter bolt portions and having a plurality of surfaces spaced at varying distances from said bolt portion, said surfaces being adapted to engage said standard respectively in different positions of said spacer block to positively maintain the adjustment of said standard, and means on the bolt portions for clamping the plate, beam and standard together.

15 9. A clamping and adjusting device for a standard of a disk plow, said plow having a beam and front supporting means and rear supporting means for the beam, said device including a clamp engaging the beam and including a plate adapted

20 to be clamped against said beam, clamping bolt portions extending in spaced relation to the plate below the beam at either side of said standard, said standard being adapted for rearward inclination for

25 trash covering, spaced bolt portions traversing the plate above the beam on either side of said standard, the spacing of the latter bolt portions being such as to provide for pivotal adjustment of said standard by sliding between the limits defined by the latter bolt portions, a spacer block adapted to be placed on one of said bolt portions and having a plurality of surfaces spaced at varying distances from said bolt portion, said surfaces being adapted to engage said standard respectively in different positions of said spacer block to positively maintain said standard in a rearwardly inclined adjustment, and said block being adapted to be placed on the other bolt portion to positively maintain said standard in a forwardly inclined adjustment, and means on the bolt portions for clamping the plate, beam and said standard together.

ALVAH E. RUTTER.
